(57) **CLAIM**

We claim the ornamental design for a tool holder with suction cups, as shown and described.

DESCRIPTION

FIG. 1 is a front elevation view of a tool holder with suction cups showing our new design;

FIG. 2 is a side elevation view thereof;

FIG. 3 is a bottom perspective view thereof;

FIG. 4 is a bottom perspective view thereof as seen at an alternate angle;

FIG. 5 is a bottom plan view thereof;

FIG. 6 is a top plan view thereof;

FIG. 7 is a top and left side perspective view thereof; and,

FIG. 8 is a top and right side perspective view thereof.

The broken lines shown in the drawings illustrate portions of the tool holder with suction cups that forms no part of the claimed design.

1 Claim, 3 Drawing Sheets
